VOLUME CONTROL DEVICE FOR RADIO-
RECEIVERS

Carmine J. Caggiano, Ozone Park, N. Y.

Application March 18, 1933, Serial No. 661,443

6 Claims. (Cl. 250—20)

This invention relates to a volume control device for radio receivers.

One of the features of the invention resides in a device for manually regulating the passage of the antenna energy to a radio receiving apparatus, downwardly from its maximum strength, to selectively control the signal strength passing to the receiver and thus vary the volume of the sound produced thereby.

10 Another feature of the invention is to provide a normally broken lead-in conductor to a radio receiver which is closed by physical contact with spaced adjacent terminal ends of the conductor and wherein the degree of compression between the hand of an operator and the terminal ends causes a variance in the antenna energy passing to the receiver, and accordingly produces a corresponding variance in the volume of tone emanating from the sound reproducer of the radio receiver.

15 A further object of the invention is to embody in a device of the above kind, a baton provided with a normally open switch in the hand grip portion thereof which is adapted to be clasped by the hand of an operator to bridge the terminals, and by the varying of the pressure of the fingers of the hand upon the terminals while waving the baton in beat time with the music emanating from a radio receiver, the operator 20 may control the volume of the sound and in so doing, impersonate an orchestra or band leader for his own amusement and the wonder and amusement of others present.

25 A further object of the invention is the provision of a device of the kind above mentioned which when not in use, the switch may be closed to permit of the full antenna energy passing to the radio receiver.

30 A still further object is to provide a device having the above features which is simple of construction, inexpensive of manufacture, and operable by one unskilled in the art of music expression.

35 With these and other objects in view, the invention resides in the certain features of construction, novel combination and arrangement of parts, and illustrated in the accompanying drawing, in which:

40 Figure 1 is a perspective view showing the device attached to a radio receiver and supported in the hand of an operator.

45 Figure 2 is an enlarged side elevational view of a baton constructed in accordance with the invention.

Figure 3 is a detail vertical sectional view on the line 3—3 of Figure 2.

Figure 4 is an enlarged horizontal sectional view on the line 4—4 of Figure 3.

Figure 5 is a diagrammatic view illustrating the manner in which the device is arranged in a radio antenna circuit.

Figure 6 is a detailed vertical sectional view of a modified form.

Referring to the drawing by reference characters the numeral 10 designates my invention in its entirety which includes a baton 11 provided with a hand grip portion 12 at one end, in the present instance, the hand grip 12 is shown separate from the baton 11 and is detachably connected thereto by providing a socket 13 on the inner end of the hand grip section into which a pin or reduced shank 14 formed on the lower end of the baton section 11 extends. This construction provides a friction fit between the two parts to enable separation of the same for a purpose to be presently explained. The hand grip section 12 is constructed of insulating material and the inner end of the same is reduced and receives a fixed contact element 15 which in the present instance is shown as a metallic ring or ferrule. Slidably mounted upon the hand grip section 12 is a movable contact element 16 also in the form of a metal ring and from which a resilient contact finger 17 extends for contacting engagement with the fixed contact element 15. By the sliding of the contact element 16 upon the hand grip section 12, the resilient contact finger 17 may be moved into and out of contacting engagement with the fixed contact 15.

In Figure 5 of the drawing, I have illustrated the invention as arranged in a radio antenna circuit A, there being a flexible wire 18 connected to the slidable contact element 16 and which in turn is connected to the lead-in from the radio antenna B, while a flexible wire 19 has one end connected to the fixed contact element 15 and its opposite end to the antenna lead-in terminal C of a radio receiver D. To attach the device to an installed radio apparatus, it is only necessary to break the lead-in wire from the aerial and connect the wire 18 therewith while the wire 19 is connected to the aerial terminal post of the radio receiver. The wires 18 and 19 have sufficient slack in them to permit of the free use of the device in the manner now to be explained.

Assume that it is desired to control the volume of the sound produced by the radio receiver, and the sound being produced is a musical composition. The operator picks up the baton by the

hand grip section 12 and moves the slidable contact element 16 so that the contact finger 17 is out of engagement with the fixed contact element 15, thus the antenna circuit to the radio receiver is broken. By arranging his fingers about the lower contact element 16, and with his thumb on the fixed contact element 15, the antenna circuit is again closed, but not to the extent of its fullest conductive capacity. It will be appreciated that normally when the movable contact element 16 is out of engagement with the fixed contact element 15 an air gap is created within the antenna circuit which in nature is highly resistant, thereby preventing the passage of the energy picked up by the antenna to the radio receiver. With the fingers of the hand of an operator pressed firmly or lightly across the two contact terminals to bridge the same, the resistance between these contact terminals varies more or less according to the pressure or compression physically applied thereto. Thus the antenna energy transferred to the radio receiver is increased or diminished according to the pressure or compression of the physical contact made by the fingers of the hand of an operator. When the physical pressure upon the contact terminals is heavy, the volume of the sound produced by the receiver is increased, whereas a light physical pressure imparted to the terminal contacts will cause the radio receiver to produce a lighter volume of sound. Thus by the variance of this physical pressure, the sound produced by a radio receiver may be selectively controlled, and in practice the operator may wave the baton in the air similar to an orchestra or band leader to beat the time of the music emanating from the sound reproducer of the radio receiver. Much enjoyment can be derived by the user and others present may be amused and mystified by the action produced.

When the device or instrument 10 is not in actual use, the movable contact element 16 may be slid to cause the contact finger 17 thereof to engage the fixed contact 15 whereby the maximum antenna energy is free to pass to the radio receiver. Also if desired the baton section 11 may be separated from the hand grip section 12 and a person seated adjacent the radio may hold the hand grip section 12 and manipulate the same in the manner above explained for the purpose of obtaining a better expression of music produced by a radio receiver.

In Figure 6 of the drawing, a slightly modified form of the invention is shown wherein the hand grip section 12' is provided with a central passage 20 into which an electric cord 21 passes. The cord 21 houses the wires 19' and 18', the former being connected to the fixed contact element 15' and the latter to the movable contact element 16'. The sliding contact element 16' is provided with a resilient contact finger 17' adapted to engage the contact element 15' and for permitting the wire 18' to move with the movable contact element, a slot 22 is provided in the hand grip section 12, and through which the said wire extends. In this construction, the wires pass out through the end of the hand grip section instead of individually hanging from the sides thereof. The operation of this form is identical to that above described.

While I have shown and described what I deem to be the most desirable embodiment of my invention, I wish it to be understood that such changes as come within the scope of the appended claims may be resorted to if desired.

Having thus described the invention, what I claim as new and desire to secure by Letters Patent of the United States, is:—

1. In combination, a radio receiving and sound reproducing apparatus, a normally open aerial circuit therefor, a hand grip member, a pair of spaced contact terminals provided on said hand grip member and arranged in said aerial circuit whereby an operator grasping said hand grip member and bridging the spaced contact terminals may by physical pressure manually control the amount of antenna energy passing to said radio receiving and sound reproducing apparatus. 80

2. In combination, a radio receiving and sound reproducing apparatus, a normally open aerial circuit therefor, a hand grip member, a pair of spaced contact terminals provided on said hand grip member and arranged in said aerial circuit whereby an operator grasping said hand grip member and bridging the spaced contact terminals may by physical pressure manually control the amount of antenna energy passing to said radio receiving and sound reproducing apparatus, and bridge conductor means for electrically connecting said spaced contact terminals when the hand grip member is released to close the aerial circuit to enable the maximum antenna energy to pass therethrough. 90

3. In combination, a radio receiving and sound reproducing apparatus, a normally open antenna circuit therefor, a baton having a hand grip portion, a pair of spaced contact terminals provided on the hand grip portion of said baton and arranged in said antenna circuit whereby an operator by grasping the hand grip portion of said baton and bridging the spaced contact terminals may manually control the amount of antenna energy passing to said radio receiving and sound reproducing apparatus by varying the physical pressure applied to said contact terminals by the operator's hand and simultaneously wave said baton in beat time with music emanating from said radio receiving and sound reproducing apparatus. 105

4. In a device of the class described, a hand grip member, a pair of spaced electrical contact elements surrounding said hand grip member and insulated from each other and adapted to be bridged by the hand of an operator grasping said hand grip member, and wires leading from the contact elements and adapted to be arranged within a circuit of the radio receiving apparatus substantially as and for the purpose specified. 110

5. In a device of the class described, a hand grip member of insulated material, a fixed contact element mounted on said hand grip member, a movable contact element slidably mounted on said hand grip member movable into and out of contacting engagement with said fixed contact element, said contact elements adapted to be bridged by the hand of an operator when out of contacting engagement with each other, and wires leading from the contact elements and adapted to be arranged within a circuit of a radio receiving apparatus substantially as and for the purpose specified. 125

6. A sound control attachment for use in connection with radio receiving apparatus comprising a member having a hand grip portion constructed of insulated material, a fixed contact element mounted on the hand grip portion of said member inwardly of the adjacent end thereof, a movable contact element slidably mounted on the hand grip portion for movement into and out of contacting engagement with said 140

stationary contact element, said contact elements adapted to be bridged by the hand of a person grasping the hand grip portion of said member when the movable contact element is out of contacting engagement with said stationary contacting element, and wires leading from both of the

contact elements and adapted to be connected with the aerial lead-in wire and aerial terminal of a radio receiving apparatus substantially as and for the purpose specified.
